ART OF CRACKING HYDROCARBONS.

BEST AVAILABLE COPY

Application filed July 7, 1921. Serial No. 482,964.

To all whom it may concern:

Be it known that I, FRED G. NIECE, a citizen of the United States, residing at Cleveland, in the county of Cuyahoga and State 5 of Ohio, have invented a new and useful Improvement in the Art of Cracking Hydrocarbons, of which the following is a specification.

This invention relates to improvements in 10 the art of cracking hydrocarbons.

The primary object of this invention is to subject hydrocarbon oil heavier than gasoline to such improved and novel treatment as 15 to produce gasoline of better quality and in larger quantity per measure of heavier oil.

Another object is to obtain a remarkably high percentage of saturated hydrocarbons, after having properly started the operation of the apparatus employed in practising my 20 improved process, without resorting to a hydrogen-supply source external to the liquid hydrocarbon to be cracked during said operation.

Another object is not only to subject liquid 25 hydrocarbon heavier than gasoline to the heat of and within a molten body composed of low-melting metal or material such, for instance, as lead heated to and not vaporizable at the required hydrocarbon-cracking 30 temperature, but to subject vapors and gases issuing from heated liquid hydrocarbon to the heat of and within said molten body in a closed chamber having a vapor-outlet, and, while said gases and vapors are being sub- 35 jected to the heat of and within said molten body, to effect the subjection, to the heat of and within said molten body, of hydrocarbon vapors and gases which have passed uncondensed through a condenser of the sys- 40 tem comprising the aforesaid apparatus, after having been subjected to the aforesaid temperature, and furthermore to so extensively and thoroughly dissociate the atomic constituents of molecules of said gases and 45 vapors from the condenser and in such intimate association with the cracking of the first-mentioned vapors and gases within the molten body that much needed free hydro- 50 gen is economically and plentifully pro- duced.

Another object is to cause hydrocarbon 55 gases and vapors from the condenser, and the liquid hydrocarbon to be cracked, to be forced under a desirable pressure into and to ascend within said molten body, and to

maintain said vapors and gases from the condenser, gases and vapors issuing from heated liquid hydrocarbon to be cracked, and vapors and gases formed during the subjection of hydrocarbons to the heat of and within said molten body, in highly intimate or close association during said subjection of said hydrocarbons to the heat of and within said molten body.

With these objects in view, and to attain 60 any other object hereinafter appearing, this invention consists in the novel steps or process hereinafter described and pointed out in the claims.

Novel and improved apparatus, suitable 70 for use in practising said process and claimed in a separate application, Serial Number 484,293, for United States Letters Patent, is illustrated in the accompanying drawings in which Figure 1 is a side elevation, largely 75 in section and partly diagrammatic. Fig. 2 is a horizontal section taken along the line 2-2 in Fig. 1, looking downwardly. Fig. 3 is a horizontal section taken along the line 80 3-3 in Fig. 1, looking upwardly.

Referring to said drawings, 5 indicates the casing of a heating furnace shown as comprising an oil-burner 6 arranged as required to have the flame or fire 7 issuing therefrom, during the operation of the furnace, enter 85 the combustion and heating chamber 8 through an aperture 9 in the furnace-front. The forward portion of said chamber extends rearwardly from and above the aperture 9, and the rear portion of said chamber extends farther upwardly, as at 10, and discharges at its upper end into a flue 11 communicating at its lower end, as at 12, with a stack 13.

Surrounded by the portion 10 of said chamber is a hydrocarbon-cracking receptacle shown consisting of a base 15, a top section 16 and an intermediate section 17. The base 15 is secured in place in any approved manner, and the top section 16 is arranged above and externally of the furnace-casing 5. The intermediate section 17 is formed by a vertical tube which is circular in cross-section and extends between the base 15 and the top section 16. Said tube may have 100 any suitable dimensions such, for instance, as a diameter of from ten to twelve inches and a height of from eight to twelve feet. Said tube forms the surrounding wall of the main portion of the hydrocarbon-crack- 110

ing chamber, and the base 15 has a cavity 18 which forms the lower end of said chamber. The tube 17 communicates at its upper end with the chamber 19 formed interiorly of the 5 top section 16 and forming the upper end portion of the hydrocarbon-cracking chamber. Preferably adjacent ends of the base 15 and tube 17 are welded together, and adjacent ends of the top section 16 and tube 10 17 have external flanges 20 removably secured together, as at 21, by bolts and nuts. The chamber 19 of the top section is closed at its upper end by a head 22 removably secured to the body of said section by bolts 15 and nuts, as at 23. Preferably the chamber 19 measures in diameter at its lower end substantially the same as the internal diameter of the tube 17, and is diametrically larger above its lower end portion. An outwardly and downwardly extending pipe 25, having a normally closed valve 26, communicates with the chamber 19 at the lower end portion of said chamber.

Within and centrally of the lower end 25 portion of the hereinbefore mentioned hydrocarbon-cracking chamber is a bell-shaped baffle-member 27 of steel. Said baffle-member is rigid with an upright tubular member 28 which has its upper portion arranged 30 internally and centrally of said baffle-member and is threaded at its lower end into the base 15. The tubular member 28 discharges into the upper portion of the chamber 29 formed interiorly of said baffle-member, and 35 communicates with a bore 30 formed in the base 15.

A pipe 31 for conducting fuel oil, or other liquid hydrocarbon to be cracked, extends 40 from above and into the portion 10 of the heating chamber to the base 15 to which said pipe is secured. Said pipe 31 discharges through the bore 30 into the tubular member 28. The pipe 31 is shown covered, from the base 15 to a point near the upper end of 45 the portion 10 of the heating chamber, with heat-resisting material such, for instance, as asbestos 32, and said pipe therefore has uncovered the upper end of its portion which extends through said chamber, so that the 50 liquid hydrocarbon is preparatorily heated but not overheated while being fed by said pipe. A diagrammatically illustrated oil-pump 33, arranged externally of the furnace, is interposed between the pipe 31 and a pipe 34 for supplying liquid hydrocarbon to 55 be cracked. Said pump is employed in forcing liquid hydrocarbon from the oil-supply pipe 34 into the pipe 31 which has a diagrammatically illustrated check-valve 35 for preventing reflux of oil in said pipe.

A vapor-conducting pipe 36, forming the vapor-outlet of the hereinbefore mentioned hydrocarbon-cracking receptacle, communicates with the diametrically larger portion 60 of the chamber 19 in the section 16 of said

receptacle and discharges into the vapor-receiving upper end of the upright worm 37 of a condenser. Said condenser comprises a tank 38 containing said worm and kept supplied with cold water. The lower 70 end of said worm forms the outlet of the condenser for the liquid or condensate resulting from condensation of vapor in said worm and discharges into the upper portion of a container or receiver 39 for receiving, 75 not only said condensate from the condenser, but gases and vapors which have not been condensed in their passage through the condenser. A pipe 40, having a normally closed valve 41, is arranged to conduct gases 80 and vapors from the upper end of the receiver 39, and a diagrammatically illustrated gas-pump 43 is interposed between the pipe 40 and a pipe 44 and employed in forcing gases and vapors into the pipe 44 85 from the pipe 40. A pipe 45, employed in supplying external hydrocarbon gas when desired and having a normally closed valve 46, communicates with the pipe 40 at a point between the valve 41 and the gas-pump 43. 90 The receiver 39 is provided with a drain-pipe 47 having a normally closed valve 48. The receiver 39 is provided at its upper end with a pipe 49 having a normally closed valve 50 and employed, when desired, in permitting the escape of spent or surplus gases from the receiver. The head 22 of the top section 16 of the hydrocarbon-cracking receptacle is provided centrally with a chamber 51, and the pipe 44 comprises a short 100 pipe-section 52 discharging into said chamber and connected by a union or coupling 53 with the remainder of said pipe. Three substantially corresponding pipes 55 are secured, in any approved manner, to the bottom of the chamber 51 and spaced circumferentially of the central portion of said bottom, as shown in Fig. 2, and communicate at their upper ends with said chamber and therefore are in communication with the pipe 44. The pipes 55 extend downwardly 105 from the chamber 51 into the lower portion of the hydrocarbon-cracking chamber. The lower end portions of the pipes 55 extend through and below a circular perforated 110 steel baffle-plate 56 arranged substantially horizontally over and near but spaced from the bell-shaped baffle-member 27. The baffle-plate 56 is central in relation to and spaced in the main from the surrounding wall of 115 the hydrocarbon-cracking chamber and (see Fig. 3) has several lugs 57 spaced circumferentially of said plate and arranged to operate with said wall in preventing horizontal displacement of said plate. The 120 baffle-member 27 is shown smaller diametrically than the baffle-plate 56. The baffle-plate 56 has a central hole or passage 58 extending vertically through the plate and also has several holes or passages 59 formed in 125

59 formed in 120

proximity to and spaced circumferentially of said central passage. The baffle-plate 56 flares downwardly from its central passage 58 and is welded to the pipes 55 which are 5 preferably in close proximity to the outer circumferential edge of said plate. The pipes 55 have their lower and discharging ends arranged under the baffle-plate 56 and over the bell-shaped baffle-member 27 and 10 bent, as at 60, inwardly and toward a point which is below said pipes but central over said baffle-member. Obviously the baffle-plate 56 connects together and braces apart the lower end portions of the pipes 55, and 15 said pipes are similarly connected together and braced apart in the upper end portion of the tube 17 by a perforated baffle-plate 61, and are furthermore connected together and braced apart at a point centrally between the 20 baffle-plates 56 and 61 by an intermediate perforated baffle-plate 62. The baffle-plates 61 and 62 are therefore rigid with the pipes 55, and said plates substantially correspond in dimensions, contour and construction, or 25 characteristics, with the lower baffle-plate 56.

The joints between component parts of the apparatus are rendered fluid-tight and furthermore formed in such a manner as to withstand heat and strains to which said parts may be subjected, but means for forming such joints are too well known to require description and illustration in this specification. Also, in making said component parts, such metal or material as will withstand the 30 heat and wear and tear to which said parts may be subjected is employed.

The hereinbefore mentioned hydrocarbon-cracking chamber is supplied with a low-melting metal or material such, for instance, 35 as lead which is readily penetrable, in a molten condition, by hydrocarbon fluids and meltable at a temperature of about three hundred and thirty degrees centigrade and therefore at a temperature lower than the hereinafter specified hydrocarbon-cracking temperature required to be established and maintained in said chamber during the operation of the system but is not vaporizable at said hydrocarbon-cracking temperature. 63 40 indicates a molten column or body resulting from the melting of a mass of small pieces of solid lead supplied to the hydrocarbon-cracking receptacle preferably preparatory to the application of the head 22 of said receptacle. In applying said head 22 the pipes 55 and connected baffle-plates 56, 61 and 62 are lowered into the tube 17, and consequently into the molten body 63. Said head 22, upon being secured in place, closes the 45 upper end of the hydrocarbon-cracking chamber, and preferably such a quantity of low-melting metal is introduced into said chamber that, during the subjection of hydrocarbons to the heat of and within the molten body 63, the surface of said molten

body is below the upper extremity of the tube 17 and above the upper baffle-plate 61 so that all of the baffle-plates are arranged in and transversely of the molten body. The hereinbefore mentioned furnace is operated 70 as required to heat the hydrocarbon-cracking chamber and contents to and maintain them at a hydrocarbon-cracking temperature varying from about four hundred to about seven hundred and fifty degrees centigrade 75 according to the nature of the liquid hydrocarbon to be treated, and the molten body 63 is therefore maintained at said temperature during the operation of the system. Said operation is preferably started by opening 80 the valve 46, while the valve 41 remains closed, and operating the oil-pump 33 and gas-pump 43, to force hydrocarbon gas from the pipe 45 to the pipe 44 and thence through the chamber 51 and pipes 55 into the lower 85 portion of the molten body 63, and to force liquid hydrocarbon from the pipe 34 to the pipe 31 and through the chamber 29 in the baffle-member 27 into the lower portion of 90 said molten body, until the development, on the molten body, of a desired gas pressure 95 preferably considerably greater, per square inch, than the pressure exerted at the base of and by the molten body per se. Hydrocarbon gas pumped from the pipe 45 is not 100 essential, because both valves 41 and 46 may be kept closed while pumping liquid hydrocarbon into the molten body 63 so as to permit establishing a desired gas pressure by 105 the gases resulting from the heating of liquid hydrocarbon in the inner chamber 29 and in the molten body. Were a gas pressure of one hundred and fifty pounds per square inch on the molten body 63 to be established, then as soon as such pressure 110 has developed in the system the valve 46 is closed, if not already closed, and the valve 41 opened and left open for establishing a continuous circulation of hydrocarbon fluids 115 in the system. With a gas pressure of one hundred and fifty pounds per square inch on the molten body 63, and with the exertion by said molten body per se at its base of a pressure of forty pounds per square inch, the oil-pump 33 is operated as required to 120 effect the delivery of liquid hydrocarbon supplied by the pipe 34 preferably under a pressure of about one hundred and ninety pounds per square inch, and the gas-pump 43 is operated as required to force hydrocarbon gases and uncondensed vapors supplied through the receiver 39 from the condenser into the molten body, and therefore an adequate continuous delivery, into the 125 molten body, of gases and uncondensed vapors from the condenser and of liquid hydrocarbon from the pipe 31 is insured. That is, during the operation of the system liquid hydrocarbon is continuously forced from the pipe 34 to the inner chamber 29 and thence 130

downwardly through said inner chamber into the lower portion of the molten body, and while liquid hydrocarbon is being forced from said inner chamber into said portion of the molten body, gases and vapors from the condenser are continuously forced into said molten body, and vapors and gases (including gasoline vapors) continuously ascend to the surface of said molten body and thence to the pipe 36 and are conducted by said pipe into the worm 37 of the condenser. Distillate or liquid resulting from condensation of vapors in the condenser and entering the receiver 39 is periodically drained through the pipe 47. Gases and uncondensed vapors discharged into said receiver from the condenser are, by and during the operation of the gas-pump 43, supplied to the pipe 44 and thence forced into and through the chamber 51 and connected pipes 55 into the lower portion of the molten body 63.

tion of the molten body 63. The liquid hydrocarbon to be cracked, being heated in the pipe 31 where the latter extends through the portion 10 of the furnace, is obviously discharged, in a heated condition, into the inner chamber 29, and, as said inner chamber is covered and surrounded by the molten body 63, the already heated liquid hydrocarbon is still further preparatorily heated internally of said inner chamber by heat transmitted through the walls of said inner chamber from said molten body and to such an extent that the hot liquid hydrocarbon, when it passes from within said inner chamber into the molten body, has been heated substantially to or somewhat above the melting point of the lead or material composing the molten body, so that said liquid hydrocarbon is in a desirable condition for entering without chilling the molten body. Also, it will be observed that vapors passing to and uncondensed through the condenser from the hydrocarbon-cracking temperature in the molten-body-containing chamber or receptacle and gases accompanying said vapors, are not only forced into the lower portion of the molten body 63 but heated, in their passage through the chamber 51 and pipes 55, to a temperature substantially as high as the melting point of the material composing the molten body, so that said vapors and gases are discharged in a desirably heated condition into the molten body. The heated liquid hydrocarbon forced into the inner chamber 29 is in the main still liquid while passing from said chamber into the molten body 63 and ascends externally of the baffle-member 27, and said heated liquid hydrocarbon and accompanying gases and vapors, and vapors and gases resulting from the subjection of said liquid hydrocarbon to the heat of and within the molten body, ascend under and toward the baffle-plate 56 and into intimate association with the hot intermediate baffle-plate 62. Said intermediate baffle-plate is helpful in producing and maintaining an intimate association of vapors and gases from the condenser and gases and vapors arising from liquid hydrocarbon in the molten body between said plate and the lower baffle-plate 56 and in retarding the ascent of said liquid hydrocarbon from between said plates. Hydrocarbons between the baffle-plates 56 and 62 ascend to and through the holes or passages in the intermediate baffle-plate 62. The upper baffle-plate 61 operates substantially the same as the intermediate baffle-plate 62 and is helpful in producing and maintaining an intimate association of hydrocarbons ascending toward said upper baffle-plate from the intermediate baffle-plate. Obviously the baffle-plates 56, 61 and 62 constitute means whereby is effected a baffling, at different heights in the molten body and above all discharges of hydrocarbons into the molten body, of ascending hydrocarbons, because each baffle-plate is instrumental in temporarily obstructing movement of ascending hydrocarbons in the molten body. Hence by the baffling means comprising the baffle-plates 56, 61 and 62 is insured a highly intimate and close association of hydrocarbons between adjacent baffle-plates and between the lower baffle-plate and the baffle-member 27 while said hydrocarbons are subjected to the heat of and within the molten body. The hereinbefore described process has been found highly efficient for the economical production of gasoline of better quality and in larger quantity per measure of liquid hydrocarbon to be cracked, with no appreciable loss of material, and with little or no appreciable formation or accumulation of carbon in any portion of the apparatus. Furthermore, were an undesirable accumulation of carbon to occur in treating some hydrocarbons after operation of the system 130

continuously for many days, said carbon will be found in a finely divided state and mainly, if not entirely, in the top section 16 of the hydrocarbon-cracking receptacle. 5 The pipe 25 can be employed as an outlet for carbon in case of an undesirable accumulation of carbon in said section 16. The base 15 of the hydrocarbon-cracking chamber is shown provided with a drain-pipe 65 10 through which, upon opening a normally closed valve 66 with which said pipe is provided, the molten metal may be drained from said chamber. Obviously upon stopping the operation of the apparatus and 15 removing the molten metal 63 through the pipe 65, only detachment of the pipe 36 from the section 16, and the required manipulation of the coupling 53 as required to separate the pipe-section 52 from the remainder of 20 the pipe 44, are required to render said section 16 free to be hoisted and removed, for cleaning or other purposes, upon detaching said section 16 from the tube 17. Also, only 25 said manipulation of said coupling and detachment of the head 22 are required to render said head and connected pipes 55 and baffle-plates 56, 61 and 62 free to be hoisted and removed.

Helpful to the efficiency of the hereinbefore described process is the forcing of hydrocarbons to be cracked into a molten body 63 which, without the necessity of introducing an external pressure medium into the system, is placed under a pressure considerably greater than the pressure exerted at its base by said molten body per se, but more especially important to a remarkably successful carrying out of said process is the baffling of ascending hydrocarbons in said 40 molten body, at different heights in the molten body, so as to insure such an extensive and thorough cracking of gases and vapors from the condenser, in such intimate association in the molten body with other 45 hydrocarbon vapors and gases being cracked in the molten body, that an adequate supply of much needed free hydrogen is obtained for producing saturated hydrocarbons without resorting to a hydrogen-supply 50 source external to the liquid hydrocarbon to be cracked, and that, per measure of said liquid hydrocarbon, gasoline in considerably larger quantity and of better quality is produced.

55 The condensate accumulating in the condensate-collecting chamber formed by the receiver 39 of the hereinbefore described apparatus is a remarkably clean-appearing and translucent liquid which, with great facility 60 and at a remarkably low cost, is chemically treatable in any approved manner to produce a clean and transparent high-grade gasoline especially well adapted for use as a highly economical fuel for internal combustion engines of motor-vehicles and mate-

rially influential in improving the operation of such engines and in increasing the mileage of such vehicles per gallon of gasoline consumed.

My invention broadly embraces a process 70 in which not only are hydrocarbon vapors and gases escaping from a hydrocarbon-cracking chamber passed through a condenser and thereby subjected to a condensing temperature, but in which gases and 75 vapors passing uncondensed through said condenser, and fresh or newly produced vapors and gases which have issued from heated liquid hydrocarbon, are simultaneously subjected to the heat of and within one 80 and the same hydrocarbon-heating molten body and preferably in such intimate association within said molten body that cracking of newly produced gases and vapors issuing from heated liquid hydrocarbon and 85 cracking of uncondensed vapors and gases from the aforesaid condenser occur in mutually influential proximity to each other within said molten body.

I would here remark that a considerable 90 portion of the vapors and gases passing with the condensate from the condenser into the condensate-collecting chamber consists of illuminants or unsaturated hydrocarbon compounds (C_nH_2n), that in treating fuel oil 95 of from 32° to 34° Baumé from ten to thirty per cent of the vapors and gases passing into the condensate-collecting chamber from the condenser will be found to consist of illuminants or unsaturated compounds, and 100 that the subjection of gases and vapors which have passed from the condenser into the condensate-collecting chamber to and within a hydrocarbon-heating molten body 105 and in association with the subjection of vapors and gases newly produced from liquid hydrocarbon heavier than gasoline to and within said molten body results in the desired production of saturated hydrocarbon 110 compounds without resorting to a hydrogen-supplying source external to the liquid hydrocarbon to be treated. Of importance, therefore, in order to obtain the maximum production of high-grade gasoline from a given quantity of liquid hydrocarbon heavier 115 than gasoline, are the passing not only of the condensate formed in the aforesaid condenser, but of all hydrocarbon gases and vapors passing uncondensed through the 120 condenser, into a closed condensate-collecting chamber having a vapor-outlet, and the subjection of gases and uncondensed vapors received by said chamber from said condenser to the heat of and within a molten body during the subjection, to the heat of 125 and within said molten body of gases and vapors newly produced from liquid hydrocarbon.

Highly satisfactory results have been obtained by practising my improved hydro-

carbon-treating process in the hereinbefore described manner in accordance with which it will be observed that, during maintenance, on top of the molten body, of a pressure which, per square inch, is at least and preferably considerably more than one hundred pounds greater than the pressure exerted at its base by the molten body per se, occurs the supplying of uncondensed gases from the condenser into the closed upper chamber 51 above the molten body while liquid hydrocarbon is forced through the inner or lower chamber 29 at the lower portion of the molten body, and gases are fed from said upper chamber 51 into the lower portion of the molten body and discharged into the molten body at a height above the discharge of liquid hydrocarbon into the molten body, so that liquid hydrocarbon cannot come in contact with gases from the condenser until after said liquid hydrocarbon has entered the molten body and vapors and gases newly produced from said liquid hydrocarbon are ascending within the molten body.

25 What I claim is—

1. In the art of cracking hydrocarbons, a process which comprises subjecting to a condensing temperature hydrocarbon vapors and gases passing from a hydrocarbon-cracking chamber, feeding other hydrocarbon into a molten body through an inner chamber in said molten body, and while hydrocarbon is discharged from said inner chamber into said molten body effecting the subjection, to the heat of and within said molten body, of hydrocarbon gases and vapors remaining uncondensed during the subjection of the first-mentioned vapors and gases to the aforesaid condensing temperature.

2. In the art of cracking hydrocarbons, a process which comprises subjecting to a condensing temperature hydrocarbon vapors and gases escaping from a hydrocarbon-cracking chamber, feeding liquid hydrocarbon into a molten body through a chamber formed at the lower portion of said molten body, and while liquid hydrocarbon is passing from the last-mentioned chamber into said molten body effecting the subjection, to the heat of and within said molten body, of gases and vapors remaining uncondensed during the aforesaid subjecting of the first-mentioned vapors and gases to a condensing temperature.

3. In the art of cracking hydrocarbons, a process consisting in forcing liquid hydrocarbon heavier than gasoline into a molten body penetrable by hydrocarbons and heated to but not vaporizable at the required hydrocarbon-cracking temperature, and above the discharge of liquid hydrocarbon into said molten body feeding into the molten body hydrocarbon vapors and gases which have passed uncondensed through a condenser

after having been subjected to said temperature, and above the discharge of gases and vapors from the condenser into said molten body temporarily obstructing movement of hydrocarbons ascending in the molten body.

4. In the art of cracking hydrocarbons, a process which comprises subjecting to a condensing temperature hydrocarbon vapors and gases escaping from a hydrocarbon-cracking chamber, forcing liquid hydrocarbon into a molten body, and in said molten body temporarily obstructing the movement of ascending hydrocarbons at a point over and spaced upwardly from the discharge of said liquid hydrocarbon into said molten body, and effecting the discharge, into said molten body and below said point, of gases and vapors remaining uncondensed during the aforesaid subjecting of the first-mentioned vapors and gases to a condensing temperature.

5. In the art of cracking hydrocarbons, a process which comprises subjecting to a condensing temperature hydrocarbon vapors and gases passing out of a hydrocarbon-cracking chamber, feeding liquid hydrocarbon into a molten body through a chamber formed within the lower portion of and heated by heat transmitted from said molten body, and at a point spaced upwardly from the last-mentioned chamber temporarily obstructing movement of hydrocarbons ascending in said molten body, and below said point feeding into said molten body gases and vapors remaining uncondensed during the aforesaid subjecting of the first-mentioned vapors and gases to a condensing temperature.

6. In the art of treating hydrocarbons, a process consisting in subjecting to a condensing temperature hydrocarbon vapors and gases which have been subjected to a hydrocarbon-cracking temperature, feeding other hydrocarbon into a molten body through a chamber at the lower portion of said molten body, and while hydrocarbon is being fed into said molten body from said chamber feeding hydrocarbon gases, which have been subjected to and remained uncondensed at the aforesaid condensing temperature, into a closed chamber above said molten body, and conducting gases from the last-mentioned chamber into the molten body.

7. In the art of treating hydrocarbons, a process consisting in subjecting to a condensing temperature vapors and gases which have been subjected to a hydrocarbon-cracking temperature, forcing liquid hydrocarbon heavier than gasoline into the lower portion of a molten body, and while liquid hydrocarbon is being forced into said molten body feeding hydrocarbon gases, which have been subjected to and remained uncondensed at the aforesaid condensing temperature, in-

to a closed chamber above said molten body and thence into the molten body and effecting the discharge of the last-mentioned gases into the molten body at a height above the discharge of the aforesaid liquid hydrocarbon into the molten body.

8. In the art of treating hydrocarbons, a process consisting in subjecting to a condensing temperature hydrocarbon vapors and gases which have been subjected to a hydrocarbon-cracking temperature, forcing other hydrocarbon into a molten body through a chamber at the lower portion of the molten body, and while hydrocarbon is being forced into said molten body from said chamber forcing hydrocarbon gases, which have been subjected to and remained uncondensed at the aforesaid condensing temperature, into a closed chamber above said molten body, and feeding gases from the last-mentioned chamber into the lower portion of the molten body.

9. In the art of treating hydrocarbons, a process consisting in effecting the development, on top of a molten body contained in a hydrocarbon-cracking receptacle, of a pressure which, per square inch, is at least one hundred pounds greater than the pressure exerted at its base by said molten body per se and subjecting hydrocarbon vapors and gases to a condensing temperature in a condenser after having been subjected to a hydrocarbon-cracking temperature, subjecting gases remaining uncondensed upon the subjection of the first-mentioned vapors and gases to said condensing temperature, and also gases and vapors newly produced from

liquid hydrocarbon heavier than gasoline, simultaneously to the heat of and within the aforesaid molten body, and during the subjection of hydrocarbons to the heat of and within said molten body maintaining on said molten body a pressure which, per square inch, is at least one hundred pounds greater than the pressure exerted at its base by the molten body per se.

10. In the art of treating hydrocarbons, a process consisting in effecting the development, on top of a molten body contained in a hydrocarbon-cracking receptacle, of a pressure which, per square inch, is considerably more than a hundred pounds greater than the pressure exerted at its base by said molten body per se and subjecting hydrocarbon vapors and gases to a condensing temperature after having been subjected to a hydrocarbon-cracking temperature, subjecting hydrocarbons remaining uncondensed during the subjection of the first-mentioned vapors and gases to said condensing temperature, and gases and vapors newly produced from liquid hydrocarbon heavier than gasoline, simultaneously to the heat of and within the aforesaid molten body, and during the subjection of hydrocarbons to the heat of and within said molten body maintaining on said molten body a pressure which, per square inch, is considerably more than a hundred pounds greater than the pressure exerted at its base by the molten body per se.

In testimony whereof, I sign the foregoing specification, this 27th day of June, 1921.

FRED G. NIECE.
